UNITED STATES PATENT OFFICE

CHARLES W. ERICKSON, OF LOS ANGELES, CALIFORNIA

WOODWORKING

Application filed June 15, 1928. Serial No. 285,749.

This invention relates to ornamental wood working, and its general object is to provide a method of forming articles such as bowls, candle sticks, spoon holders, lamp bases, urns and the like, from pieces of wood of various kinds or colors, shaped substantially triangular in cross section and secured together in a manner to present a many sided block to be put in a lathe or wood turning machine, for turning out a plurality of formed articles of the type desired from a single block with the result that the articles can be made in numbers in an easy and expeditious manner with very little effort.

15 A further object of the invention is to provide an article of ornamental design that is formed from sections of wood of various kinds or colors, with the sections secured together by veneer strips and bands to prevent 20 splitting and separation of the sections under all climatic conditions.

Another object of the invention is to provide a method of forming articles of ornamental design, that includes a plurality of 25 sections with veneer strips or bands disposed between the sections to increase the ornamental effect.

A still further object of the invention is to provide a method of forming articles of the 30 character set forth with minimum waste of wood.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a fragmentary elevation of a 45 nut bowl constructed in accordance with my invention and showing parts thereof in section.

Figure 2 is a top plan view of a portion of the bowl as shown in Figure 1.

50 Figure 3 is a similar bottom plan view.

Figure 4 is an end elevation of one block

formed from sections of wood of different kinds or colors with veneer strips between the sections.

Figure 5 is a similar view of another block formed from a greater number of sections 55 than the block as shown in Figure 4.

Figure 6 is a fragmentary side elevation of the block as shown in Figure 4, with dotted lines to indicate the manner of forming bowls in numbers from a single block. 60

Figure 7 is a similar view illustrating the manner of forming candle sticks in numbers from a single block.

Referring to the drawings in detail, and particularly to Figures 4 to 7 inclusive, it 65 will be noted that in forming the articles such as bowls, candle sticks, spoon holders, lamp bases, urns and the like, a plurality of sections 1 of wood are formed in triangle shape in formation and secured together by 70 adhesive material, with veneered strips 2 arranged between the respective sections so as to produce an article as shown in Figures 1, 2 and 3 of the drawings.

From the Figure 6 illustration it is manifest that parts of the triangular shaped sections are cutaway at intervals upon the apices thereof to roughly constitute in combination the cup portions of adjacent bowls to be turned. These portions initially cutaway are utilized for other purposes, such as the base portions of bowls and other structures made into blocks. The pockets or cups for the bowls, initially cut, will materially lessen the labor required in turning out the 85 desired shape of cup or bowl core and big chunks or slivers will not be encountered by the wood working tools whereby the possibility of splitting the block or separating the sections incident to the encountering of the 90 wood working tools with such obstructions is overcome.

The sections when secured together present a block 3 having many sides and which by this arrangement, is easy to handle and 95 secure in a lathe or wood working machine, wherein the block is turned down to provide the articles in the form as shown in dotted lines in Figures 6 and 7. Figure 6 illustrates a plurality of articles in bowl form in dotted 100

lines and Figure 7 a plurality of articles in candle stick form. The respective article forms which are indicated by the reference numeral 4 are sawed apart and then finished in the manner as shown in Figures 1, 5 2 and 3.

While I secure the sections of the blocks together by adhesive material with veneer strips or bands between the sections, I also provide veneer strips and bands that are 10 countersunk about the articles and these bands for distinction are indicated by the reference numeral 5.

The bands 5 prevent splitting or separation 15 of the sections regardless of the climatic conditions as it will be apparent that they secure the sections together in the form as turned out. The bands 5 may be formed from strips of wood of various colors or may be formed 20 from metal such as brass.

The articles may have secured to the bottoms thereof felt pads 6 and the bowl as shown in Figure 1 is primarily designed for nuts as it will be noted that rising centrally from the bottom thereof is a nut 25 cracking anvil 7.

The strips or bands 5 are preferably arranged to encircle the base 8 of the bowl, the enlarged bowl portion 9 thereof with one of 30 the strips arranged substantially centrally of the bowl portion while other strips are disposed adjacent the upper edge, with the result the sections are materially reinforced at the top and bottom of the bowl and intermediate the ends thereof. Of course, the 35 strips will be arranged on the other articles at the most appropriate places where they will function to advantage.

From the above description and disclosure 40 of the drawings, it will be obvious that I have provided a method of forming articles of ornamental design from a plurality of sections of wood of different colors and kinds disposed in block formation whereby 45 a number of articles may be formed from a single block when the latter is disposed in a lathe or wood working machine with the result the articles can be formed in numbers with minimum waste of wood and in an 50 easy and expeditious manner.

It is thought from the foregoing description that the advantages and novel features of my invention will be readily apparent.

I desire it to be understood that I may 55 make changes in the construction and in the combination and arrangement of the several parts, provided that such changes fall within the scope of the appended claim.

What I claim is:

60 In a method of forming bowls in numbers from a single block of wood constructed by securing together a plurality of sections of wood that are substantially triangular shape in cross section and of various kinds 65 and colors to provide a block having many

sides, with veneer strips between the adjacent sides of the sections extending from the apices formed by the meeting side wall portions outwardly in line with the outer surfaces thereof, the apices of the sections being cutaway at intervals and registered to 70 form the cup portions of the bowls, applying means for securing said sections together including veneer strips and bands countersunk in the bowls circumferentially of and about the outer surfaces thereof, supporting 75 said block in a wood working machine for turning out the bowls in design formation, sawing the bowl forms apart through the cup portions and thence finishing the bowls within the cup portions.

In testimony whereof I affix my signature.
CHARLES W. ERICKSON.
